US00D955132S

(12) **United States Design Patent** (10) Patent No.: **US D955,132 S**
(45) Date of Patent: ** *Jun. 21, 2022

(54) **PORTABLE CHAIR**

(71) Applicant: **YETI Coolers, LLC**, Austin, TX (US)

(72) Inventors: **Derek G. Sullivan**, Austin, TX (US); **Andrew J. Winterhalter**, Austin, TX (US); **John Warren Dow**, Austin, TX (US); **Donald Edward Desroches**, Austin, TX (US)

(73) Assignee: **YETI Coolers, LLC**, Austin, TX (US)

(*) Notice: This patent is subject to a terminal disclaimer.

(**) Term: **15 Years**

(21) Appl. No.: **29/804,134**

(22) Filed: **Aug. 18, 2021**

Related U.S. Application Data

(63) Continuation of application No. 29/770,890, filed on Feb. 17, 2021, now Pat. No. Des. 941,600, which is a continuation of application No. 29/676,771, filed on Jan. 14, 2019, now Pat. No. Des. 912,423.

(57) **CLAIM**

The ornamental design for a portable chair, as shown and described.

DESCRIPTION

FIG. 1 is a top, front, right perspective view of a portable chair showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the portable chair form no part of the claimed design.

1 Claim, 7 Drawing Sheets
